UNITED STATES PATENT OFFICE.

JOSEPH WEATHERBY, OF NEW CUMBERLAND, PENNSYLVANIA, ASSIGNOR TO ANDREW J. DULL, OF HARRISBURG, PENNSYLVANIA.

MAGNETIC ORE-SEPARATOR.

1,024,539.

Specification of Letters Patent.

Patented Apr. 30, 1912.

Application filed August 25, 1911. Serial No. 645,958.

To all whom it may concern:

Be it known that I, JOSEPH WEATHERBY, a citizen of the United States, residing at New Cumberland, in the county of Cumberland, State of Pennsylvania, have invented a certain new and useful Improvement in Magnetic Ore-Separators; and I do hereby declare the following to be a full, clear, and exact description of the same, reference being had to the accompanying drawings, forming a part of this specification, and to the figures and letters of reference marked thereon.

My invention is an improved magnetic ore separator adapted to the separation of ores of a very low magnetic permeability, the separation of which requires a concentrated magnetic field of an extremely dense character.

Permeable particles are attracted in a concentrated field to the densest area of the poles, as for illustration: If permeable ore particles are placed between two poles of a magnet of equal facial area the various ore particles will be attracted equally to the nearest pole face. If one of the pole faces be chamfered off so as to expose a very small comparative area to its opposed pole, the lines of force will converge to the smaller area where they will be very dense, and all permeable particles will be attracted to the smaller area.

In my invention an extremely concentrated field is formed by an arrangement of two annular pole pieces having frusto-conical faces and narrow annular tips and a centrally located substantially stationary conical armature. The centrally disposed armature at its top and bottom gradually curves away from the pole faces, thus allowing its nearest areas to be located close to the wedgelike pole tips to form a very dense and concentrated field of the lines of force converging from the great armature area to the narrow pole tips.

One of the objects of the invention is to improve the machine of my prior application No. 582,334, filed September 16, 1910, and provide a compact machine having no parts liable to become disarranged or broken, and capable of operating upon and separat-

ing materials of a very widely different magnetic susceptibility, thus adapting the machine for use in the separation either of magnetite or of practically any of the low 55 grades of ores which do not exist naturally in what would ordinarily be considered a magnetic condition.

The invention contemplates the separation of materials by passing the same through 60 concentrated magnetic fields wherein the lines of magnetic influence pass through the ore particles and converge toward the pole tips and providing means whereby the more susceptible material is advanced and removed from the magnetic influence while 65 the less susceptible materials travel by gravity alone through the successive fields of magnetic influence.

In the practical embodiment of the apparatus for carrying the present invention into practice and adopted for illustrative purposes herein, the magnetic field is produced between annular pole pieces having frusto-conical faces and a centrally located 75 armature; a conical screen rotates at sufficient speed to cause the more susceptible materials to be advanced toward the discharge by centrifugal force, and an internal substantially conical stationary armature 80 which also acts as a guide constitutes the means whereby the materials of less susceptibility are guided to travel by gravity alone down through the annular fields.

The drawing is an elevation with one half 85 in section of a magnetic separator embodying the present improvements.

While any desired form of supporting and adjusting mechanism might be employed, a novel and compact arrangement 90 is shown in the accompanying drawing; that is to say, in a suitable base A there is mounted a series of vertical posts or standards A' which, at their upper ends are rigidly connected with lugs b projecting from 95 the outer face of field magnet ring B. The magnetizing coils C are located within chamber c opening into the body of the field magnet from the inner conical face.

While the pole pieces may be of different 100 formations, it is preferable that the upper pole piece B' be made integral with the field

magnet B while the tip B² of the lower pole piece is separate and in the form of a ring adapted to seat in the under side of the field magnet B after the coils C are properly positioned.

The pole piece B² is rigidly held in intimate contact with the body of the field magnet by screws b². The inner faces of the pole pieces are of frusto-conical form and 10 are preferably substantially in alignment with each other, their proximate edges forming annular tips of greatly reduced area. Thus constructed, the body of the field magnet, uprights and bases constitute a rigid 15 structure upon which the other parts of the apparatus may be conveniently mounted for proper adjustment and operation.

The arms or legs of the magnet being annular and concentric, one is of greater 20 diameter but longer than the other and in order that the magnetic conductive capacity of the arms or legs may be equal the thickness of the inner arm or leg on radial lines is considerably greater than that of the 25 outer arm or leg, the total cross sectional area of both being however substantially the same.

The hopper E is mounted on the upper 30 ends of the uprights E' secured in the upper face of the field magnet B and has a downwardly projecting centrally disposed discharge spout E² on the outside of which is located a feed adjusting sleeve F which is 35 adjustable vertically by screw thread f. In the base of adjusting sleeve F is a rigidly supported feed pipe f'. The regulation and adjustment of adjusting sleeve and pipe will hereinafter be more fully explained.

40 Suitably mounted and centrally located within the cylindrical central opening of the field magnet B and rigidly held in position at its upper end by supporting ring D and machine screws d and d' is an annular bearing housing D' which is in turn machined to support annular ball bearings G and G'. Rigidly mounted at the lower end of bearing housing D' is a conical shaped oil drip pan H which when full of oil can 45 be pumped out through oil pipe H'.

50 Accurately mounted in the center and supported by the annular ball races of ball bearings G and G' is a rotary screen having a long tubelike neck I' at its upper end 55 and a hollow coneshaped lower portion I which rotates in close proximity to the frusto-conical faces of the pole pieces. It is rotated through the medium of a belt applied to the double flanged pulley J, rigidly secured to it by threading the outer portion of the neck and the inner flange of the pulley J at J'.

60 It will be noted that the lower belt flange of pulley extends over the top of bearing

housing D', but not in rubbing contact with it and forms a practical cover to prevent dust entering the bearing chamber.

Rigidly secured by machine screws to the neck I' of the rotating screen and directly under the annular ball race of ball bearing G is a ring i' forming a shoulder to prevent the ball bearing G from being forced out of alignment when the pulley J is tightly screwed down with its lower flanged portion in contact with the top edge 75 of annular ball bearing G. On the outside and at the junction of the neck I' and conical portion of rotary screen I is a shoulder i'' which is arranged to accurately seat the ball bearing G' to take the up thrust while 80 the ball bearing G rigidly held between the lower pulley flange and shoulder ring i'' takes the down thrust.

The radial alignment is taken care of by 85 both ball bearings. Forced over the shoulder i'' is a ring i''' to guide the oil into oil drip pan H. The screen I is of non-magnetic material imperforate and adapted to operate centrifugally in feeding the more susceptible material through and away from the magnetic fields in proximity to the pole pieces.

To prevent the scattering of the magnetic 90 lines of force where they pass from the pole tips of the frusto-conical poles through the rotary screen I to the armature K and also 95 to form a path of least magnetic resistance two lines of headless screws i⁴ and i⁵ are provided. The screws extend through the rotary screen, are of magnetic material and 100 spaced close together to prevent the lines of magnetic force spreading to any great extent until they are on the acting side of the rotary screen.

Arranged centrally of the rotating screen I and directly under the feed pipe f' is a 105 substantially conical cap or guide k over the conical face of which the material from the hopper is caused to travel by gravity into a magnetic field of gradually increasing density. The conical guide is 110 preferably always of non-magnetic material and also acts in conjunction with feed pipe f' also of non-magnetic substance, as a feed adjusting gate the adjustment of which 115 will be hereinafter explained. Inasmuch as this guide together with the armature rigidly connected therewith is of some importance, it will be described with particularity, the fact being borne in mind, however, that one of the essential features resides in a conical guide having means whereby the material traveling down over the surface may be retarded in its movement so as to check its momentum and preferably means whereby such material will 120 momentarily leave the guide surface as in falling onto a step or shoulder and where the stronger magnetic particles can be more 125

freely acted upon by the magnetic energy and readily disentangle themselves from the lesser magnetic particles and the non-magnetic gangue. Another essential feature 5 sides in the shape of the armature K in its relation to the frusto-conical pole pieces B' and B². The main body of the conical armature is exactly parallel with the frusto conical faces of the poles to points at right 10 angles with the pole tips, at which points the armature at its top and bottom gradually slopes away, thus causing the ore particles in their downward flow by gravity over the surface of the guide 15 k and the armature K to enter a field of gradually increasing density to the point of maximum density thence flowing in a constantly thinning layer to and over the neutral point on the armature surface, thence through a dense concentrated 20 field of opposite sign, and thence the particles of a less susceptible character, such as gangue, fall by gravity through a field of constantly decreasing strength to the 25 discharge. The particles having permeability are attracted to the pole tip but are intercepted by the rotary screen I which revolves at such speed as to overcome the magnetic attraction by centrifugal force 30 and discharge permeable particles over a partition M which will be hereinafter described.

At the base of conical guide k and the top portion of armature K the step or shoulder 35 indicated by the letter k' is formed, such of the lesser permeable particles of ore that were not attracted to the upper pole B' in their rapid movement by gravity over the face of the conical guide k together with 40 the gangue particles, will come to a momentary rest on the shoulder formed by the armature K. This point of rest is opposite to the frusto-conical pole tip B' and directly within the upper concentrated field the 45 weaker permeable particles on their further movement by gravity will be influenced by the converging lines of force which pass through them from the armature to the pole tip to jump to the dense pole tip but are 50 intercepted by the rapidly revolving screen. Such weak permeable particles that are held back by the weight of gangue material resting on them at the top concentrated field will flow by gravity in a constantly thinning 55 layer to the lower concentrated pole where partly by the reversal of magnetism within themselves and the abrupt action of the dense field of the lower pole B² they are easily influenced to cross the air gap with 60 the converging lines of force until they are intercepted by the rapidly revolving screen. It will be particularly noted that the rest point is very essential for weak or very slightly permeable particles. Should they

enter the concentrated field with momentum, 65 their velocity would be such that they would rush to and through the concentrated field regardless of its strength without being perceptibly affected.

The armature K is rigidly supported by 70 a vertically adjustable spider O. The supporting member k² is preferably of non-magnetic material. Between the lower edge of the rotary screen and the outer lower edge of the armature there is erected an annular 75 partition M and outside of said partition, and surrounding the field magnet ring B is an inclosing ring or casing N. The rings N and M constitute the upper edges of receptacles for tailings and concentrates respectively, and said rings, together with the central armature, are preferably directly supported upon a vertically adjustable spider O whereby they may be adjusted in unison 80 so as to vary both the width of the passageway through which the materials travel between the pole pieces and the central armature and guide and the position of the edge of the partition on opposite sides of which the tailings and concentrate falls. Arranged on the spider O are a number of annular slots k³ in which various diameter annular partitions M can be placed. 85

Depending below the spider O and forming continuations of the rings M and N are 90 inverted cones or funnel shaped receivers M' and N' respectively terminating in chutes M² and N² through which the tailings and concentrates are discharged. The spider O is conveniently guided on the uprights A' and supported by sleeves O' which latter are, in turn, supported on a second spider O² the latter being upon a centrally located hand wheel nut O³ adjustable vertically on a central screw O⁴ projecting upwardly from the base A. When the hand wheel nut O³ is turned to the right or left, the spider frame supporting annular partitions M and N together with conical armature K are adjusted closer or farther away 100 from the poles, thus causing a greater or lesser air gap between the poles and armature. This adjustment is necessary for ores of a higher or lower permeability, as for instance, a strong magnetic ore on entering a 105 magnetic field will be charged by induction and form into a mass resembling fur on an angry cat's back, entangling with its gangue. It will be obvious that an ore of this character will require a greater air gap, so that 110 in a long jump to the poles it will have a reasonable chance to disentangle from its gangue. Ore of a low permeability does not bunch in clusters and owing to its weak 115 attractability requires the armature to be in close proximity to the pole pieces. When the armature K is adjusted vertically, the guide cone k which forms a feed gate in 120 125

conjunction with feed pipe f' is thrown out of normal adjustment. To replace the adjustment so that the ore will flow properly by gravity down and over the guide cone, 5 the adjustment sleeve F supporting the feed pipe f' is adjusted vertically by means of a screw thread f until the proper feed is found.

To secure the proper convergence of the 10 lines of force and an extremely dense unbroken annular field through which all the material must pass requires careful and accurate formation of the parts and while as shown both the superficial and sectional 15 areas of the armature in proximity to each pole of the magnet is greater than the said pole, the convergence of the lines of force outwardly or toward the pole tips is assisted by making the poles of material having 20 a very high magnetic conductive capacity while the armature is of material having less conductive capacity per equal area with the result that the lines of force concentrate at the poles and scatter on and 25 in the armature, but care is to be taken that the total conductive capacity of the armature is practically as great as that of the poles to prevent leakage and cause practically all of the line of force in the circuit 30 to cross the air gap through which the materials pass.

While the mechanical construction and arrangement of the parts such as the bearings, feed spout etc., may be varied the arrangement shown is advantageous in many respects. For instance, by removing the 35 screws connecting the ring or sleeve D' and supporting ring D , the conical screen and its bearings are free to be removed downwardly and may be so removed when the magnet is lifted away from its supports or the armature removed from beneath the magnet. The screen and its bearings are removed as a unit and the bearings may be 40 adjusted or cleaned without changing the adjustment.

What I claim is:—

1. A magnetic separator embodying a field magnet having continuous annular pole 50 pieces of opposite sign, forming a downwardly diverging or conical chamber having a feed opening at the apex, an imperforate conical screen journaled to rotate within the chamber in proximity to the faces of the pole pieces and an armature having a 55 conical face arranged within the screen in proximity to the faces of the pole pieces, said conical face at both top and bottom merging into curved faces extending gradually away from the pole pieces in a vertical plane, the arrangement being such as to 60 distribute the lines of magnetic force on the armature and cause them to converge toward the pole pieces.

2. A magnetic separator embodying an 65 annular field magnet having continuous annular pole pieces of opposite sign with continuous annular tips in different horizontal planes whereby a downwardly diverging or conical chamber is formed, a conical screen 70 journaled to rotate in said chamber in proximity to the pole tips and having a feed opening at the apex, a circular armature adjustable to fixed positions in said chamber, said armature having a conical face 75 parallel with the screen said face merging at both top and bottom into curved faces extending gradually away from the screen and pole tips in a vertical plane and a conical guide of non-magnetic material located centrally above the armature.

3. A magnetic separator embodying an annular field magnet having continuous annular pole pieces of opposite sign with their tips in different horizontal planes and defining a downwardly diverging chamber, the outer pole piece being of less thickness than the inner pole piece whereby the magnetic conductive capacity of the two pole pieces is equalized, a conical imperforate screen 85 journaled to rotate within the field magnet and a circular armature within the screen and having a conical face in proximity to the faces of the pole pieces.

4. A magnetic separator embodying an 95 annular field magnet having continuous annular concentric pole pieces of opposite sign with their tips in different horizontal planes, a conical screen mounted to rotate within the pole pieces and in proximity to the tips thereof and a conical armature located within the screen and having a maximum diameter greater than the diameter of the inner portion of the outer pole piece, the top and bottom of the armature being above 100 and below the tips of the inner and outer pole pieces respectively, whereby the lines of magnetic force may distribute themselves vertically on the peripheral portion of the armature.

5. In a magnetic separator the combination with a field magnet having annular concentric pole pieces of opposite sign, the outer pole piece having a tip formed by a removable ring and said pole pieces having conical faces in alinement with each other, an imperforate conical screen journaled to rotate within the pole pieces in proximity to said conical faces and an armature within the screen, said armature having a conical face extending parallel with the faces of the pole pieces and rounded faces at top and bottom into which the conical face merges without the formation of projections by which the lines of force would be caused to converge toward the armature.

6. In a magnetic separator the combination with an annular field magnet having

annular concentric pole pieces of opposite sign with their tips in different horizontal planes to form a conical chamber and a fixed conical armature within said chamber but spaced from said tips whereby a conical passage is formed between the magnet and armature, of an imperforate conical screen of non-magnetic material journaled to ro-

tate in proximity to the pole tips and inserts of magnetic material extending through the 10 screen in proximity to the pole tips.
